Primary Examiner — Sheryl Lane*Assistant Examiner* — Ieisha N Price(74) *Attorney, Agent, or Firm* — John J. Brooks, III; John Brooks Law LLC(57) **CLAIM**

I claim the ornamental design for a coring knife, as shown.

DESCRIPTION

FIG. 1 shows a top perspective view of a coring knife showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a rear elevational view thereof; and,

FIG. 7 is a front elevational view thereof.
